ARTHUR BARBARIN, OF NEW ORLEANS, LOUISIANA, AND ANTOINE ERNEST DUPAS, OF PARIS, FRANCE.

Letters Patent No. 96,074, dated October 26, 1869.

IMPROVED APPARATUS FOR CARBURETTING AIR.

The Schedule referred to in these Letters Patent and making part of the same

To all whom it may concern:

Be it known that we, ARTHUR BARBARIN, of the city of New Orleans, State of Louisiana, and ANTOINE ERNEST DUPAS, of the city of Paris, France, have jointly invented certain new and useful Improvements in Machines for Carburetting Atmospheric Air; and we do hereby declare the following to be a full, clear, and exact description of the same, reference being had to the annexed drawing, making a part of this specification.

Our invention, in general terms, may be said to consist of an improved mechanical arrangement for feeding continuously the carburetter with air; of a means for regulating the supply of air, and the pressure thereof, accordingly as a greater or less number of burners is lighted; of a means for modifying the quality of the gas or carburetted air; and finally, of a means of maintaining the exact temperature in the hydrocarbon employed to carburet the air, that will produce the best results under all conditions of latitude, as well as the varying temperature of the external air, resulting from changes of season or weather in any given season of the year.

The objects accomplished are the securing of a continuous supply of air; a waste of all the air not required to be carburetted for the exigencies of the moment; an unvarying equilibrium of the water, or other suitable liquid packing employed in the apparatus in connection with the means for supplying the air; a uniform admixture of carbon with the air that is burned; a never-varying temperature of the hydrocarbon; the combustion of all the carbon infused into the air; and, finally, an illuminating-power in the light or lights produced by the combustion of the carburetted air that has never been equalled, except by the calcium or the electric lights, commonly so called.

But our invention will be better understood by referring to the drawing, on which—

A represents a box-recipient for the revolving wheel B, and a water or other suitable liquid packing, to be used in connection therewith, the said box, wheel, and liquid packing constituting our means for continuously feeding the carburetter with the atmospheric air to be used for illuminating-purposes after it has been enriched by a proper infusion of carbon.

The box A may be of any suitable form or size, according to the exigencies of the occasion or supply of air needed, and constructed of any proper material.

The wheel B is composed in part of the scroll-formed partitions c, three in number, that terminate before reaching the axis of the wheel, so as to establish a cylindrical central open space, C, and are so placed as to leave the curved spaces between them entirely open everywhere, for the free passage of the air and water,

or other suitable liquid packing, which latter occupies the box up to the axis of the said wheel, and in part of a closed section or chamber, D, of somewhat larger diameter, that communicates with the part in which the scroll-partitions obtain by an opening that is coincident with and of the same diameter as the open central space C in the latter.

This wheel B is mounted on an axis that is composed of the solid shaft d, to which it is permanently secured, and the pipe e, around which it revolves, by means of a journal-box, f, the shaft d being connected to the pipe e, by means of a socket or sleeve-joint at g, substantially as shown at Figure 1, so that when the shaft d is rotated, through the agency of the crank E, by means of any motor that may be connected therewith, the wheel, as a whole, will revolve with it.

Any proper opening, h, so arranged as to prevent any accidental intrusion from rain, if the machine be placed in the open air, in the upper part of the box A, provides for the admission of air into the box.

The effect produced by the rotation of the wheel B, half of the same being in water, and half in the air, is obviously to force the air, which finds its way into the spaces between the partitions c, into the open space C, and from thence into the closed section D, where the outlet for its escape is through pipe e; but to prevent the extension of any considerable volume of water along with the air, we provide a vertical elbow, e', to said pipe, which rises very nearly to the interior surface of the perimeter of said concentrating-chamber D, and is covered by a cap, i, as shown on the drawing.

Any desired measure of density and consequent pressure can always be secured by an adjustment of the diameter of pipe e to the capacity of the scroll-section of the wheel for throwing air into the section D.

If a very high pressure is required, the diameter of the whole wheel must be increased, but if, on the contrary, only a slight pressure or density of the air is necessary in any given case, and at the same time a large supply of air, the diameter of said wheel must be diminished, while the length of the scroll-section along its axis must be increased; but insomuch, as with any given apparatus to supply carburetted air to more than one burner, there must always be more or less danger that the supply of air will be too great, and furthermore, despite every possible provision to prevent the same, there will always be a larger or smaller quantity of water thrown into pipe e, and carried out of the box A, it is clearly necessary, to the efficient working of our apparatus, that there shall be some agency by which any excess of air that is driven through said pipe shall be wasted before it is carburetted, and that all the water carried out of said box A shall be carried back therein in an automatic manner. The mechanical in-

strumentality we have devised for the purpose consists of a circular receiver, F, which is placed in a larger vessel, G, in such manner that an annular open space, *j*, is established around the former, and an interval equal to the distance between the walls of the two vessels be provided between the respective bottoms of the same, as clearly shown at fig. 1.

A small pipe, K, connects the outer vessel G with box A, substantially as shown, and there being an opening, *l*, in the bottom of F, it is clear that whatever the quantum of water carried out of the box into F, there will always be the same level in said box, and in G and A.

But there is also a discharge-orifice or pipe, *m*, in the vessel F, through which an excess of air thrown into the same will be forced into the circumferential space *j*, and thence find its way, by reason of its greater levity, through the water therein contained into the open air at the top of said space, which is left open for the purpose.

The apertures *l* and *m* being very small, no sudden expansion of the water from nor re-entering of the same into the vessel F can take place, nor any such violent agitation of the water occur under any circumstances whatsoever, as will appreciably affect the regularity of the flow of the gas from the same.

The expulsion of the surplus air takes place the moment the pressure of the superincumbent air forces the water in the lower sections of the vessel F down to the vent *m*, and this always takes place when the machine is properly proportioned in its several parts, before the density of the air becomes so great as to force the air through the burner or burners with such rapidity as to prevent the complete combustion of the carbon in the gas. This part of the organism therefore prevents inequality of pressure at the point of ignition, whatever the number of lights burning, and at the same time preserves the same level of water in the box A, however great the quantum that in the rapid operation of the machine may be thrown out of the same through the pipe *e*, and also prevents any sufficiently violent agitation of the water to interfere with the regular flow of the air, and may hence, with great propriety, be called the regulator or governor of our machine.

A vertical pipe, H, ascends from the centre of the vessel F into and nearly to the top of the vessel L, that is partially filled with water, or other suitable liquid, and provided with a glass gauge or pressure-measurer, *n*, properly marked and numbered.

The air coming from the regulator below, and impinging on the upper surface of the water in L, forces the same into the gauge or indicator *n*, and thus, by means of the marks and figures thereon, indicates the precise pressure to which it is subjected with unerring accuracy, and to some extent also aids to regulate the flow of the air.

From the pipe H, a pipe, M, leads into the carburettor N, entering the same near the top, and then descending, as shown by dotted lines, until it reaches very nearly to the bottom thereof; there being a perforated diaphragm, O, attached to it at its lower end, beneath which the air passing through the said pipe escapes in the operation of the machine, as shown by the arrows.

The carburettor N is provided with chamber 1 and a recipient chamber, 2, for the hydrocarbon to make the gas, the latter being considerably smaller than the former, and enveloped by an annular chamber, 3, and an open space, 4, at its bottom, in consequence of its being placed in an outside enclosing-vessel, P.

The carburettor is supplied with hydrocarbon from a reservoir or holder, R, through a pipe, *p*, which enters the former just below the gas-chamber.

The reservoir R should be air-tight when the stop-cock *t* is closed, and the aperture in pipe *p* exceedingly

small, for our method of feeding the carburettor with hydrocarbon is by pressure from the carburetted air, which will find its way through the said pipe from the carburettor into the reservoir whenever the column of the liquid is reduced to a certain point, and this makes it necessary that the latter should be absolutely air-tight, or otherwise the flow of the hydrocarbon will be too rapid into the carburettor, and might cause too much of the same to enter it for good results.

A gauge, *r*, of glass, fixed on the outside of the carburettor N, and communicating with both the hydrocarbon and gas-chambers, properly marked, indicates the height of the hydrocarbon, so that if it be too low or too high, the difficulty may be remedied by a movement of the stop-cock, not shown on the drawing, in pipe *p*.

Through a pipe, *s*, which is also provided with a stop-cock, although none is shown on the drawing, water is poured into the open space around the hydrocarbon-chamber 2 until it is nearly full. This water constitutes our means for maintaining a uniform temperature in the hydrocarbon at all seasons of the year, and under all conditions of the temperature of the surrounding air, for connected therewith, as shown, is a thermo-siphon, S, with a globe-section, S', in which, when the temperature is too low for the efficient operation of the apparatus, the water is kept from being affected thereby, by the application of the heat of a gas-jet flowing through a small pipe, *u*, that is connected with the pipe U that leads from the carburettor to the burner or burners fed by the machine.

In carburettting atmospheric air, it is very often found that the infusion of carbon is so great that it is impossible to effect its complete combustion, and that hence there is great waste of the same, and more or less smoke at the points of combustion.

We remedy this evil by connecting, with the pipe M, a branch-pipe W, and leading the same into the gas-chamber, substantially as shown, so that when the stop-cock *v* is open, uncarburetted air will be thrown into the gas-chamber, where, mingling with that which has been carburetted, it will reduce the richness of the latter to any desired extent.

In some cases it may be requisite to reduce the volume of air passing through pipe M into the carburettor, by means of the stop-cock *y*, when the above operation is going on, as well as when only a limited quantum of carburetted air is required for the occasion.

The whole apparatus may be fixed on a portable platform, H', so as to be easily transportable, or it may be permanently fixed in position on a table, shelf, floor, or anywhere else that convenience may dictate, and be used for illuminating houses, steamboats, railroad-cars, &c.

Having thus described our invention, What we claim, and desire to secure by Letters Patent, is—

1. The revolving feeding-wheel B, when constructed and mounted as described, in combination with a box-recipient, A, therefor, in which is employed a water or other suitable liquid packing, as specified, when all the parts are arranged and operate substantially as described, for the purposes set forth.

2. The receiver F, when provided with two (2) apertures *l* and *m*, and surrounded by the outer vessel G, and this latter is connected with the box A by a pipe, *k*, substantially as and for the purposes set forth.

3. The combination of the receiver F and its adjuncts with the subject of our first claim, by means of a pipe, *e*, and its elbow *e'*, substantially as described, for the purpose set forth.

4. The above combinations in combination with an indicator, L, provided with a gauge, *n*, substantially as and for the purpose described.

5. The carburettor N, when the same is divided

into the gas and hydrocarbon-chambers 1 and 2, and the latter is enveloped by the water-containing spaces 3 4, by means of an outer vessel, P, with a thermosiphon, S, in which there is a globe-section, S', when these parts are arranged, relatively to each other, as set forth, for the purpose specified.

6. The above combination in combination with the subjects of our first, second, third, and fourth claims, and a pipe, M, substantially as described, for the purpose set forth.

7. The carburetter N, when provided with the ad-

juncts herein specified, in combination with a reservoir, R, when the hydrocarbon is automatically fed from the latter, by means of pressure from the gas that passes therein from the former, in the manner herein described.
